(57) **CLAIM**

The ornamental design for a pair of advertising panels affixed to the entry portion of a shopping cart corral, as shown and described.

DESCRIPTION

FIG. 1 is a top isometric view of a pair of advertising panels affixed to the entry portion of a shopping cart corral;

FIG. 2 is a side view thereof;

FIG. 3 is a front view thereof;

FIG. 4 is a top view thereof;

FIG. 5 is a top isometric view of a pair of advertising panels affixed to the entry portion of a shopping cart corral;

FIG. 6 is a side view thereof;

FIG. 7 is a front view thereof; and,

FIG. 8 is a top view thereof.

The broken line showings of the shopping cart corral in FIGS. 1-8 are for the purpose of illustrating an environment only and form no part of the claimed design.

1 Claim, 8 Drawing Sheets
